UNITED STATES PATENT OFFICE.

JOHN L. KAUFMAN, OF BROOKLYN, NEW YORK.

PROCESS AND APPARATUS FOR MAKING NATURAL-EDGE BEAVER HATS.

1,389,364.

Specification of Letters Patent. Patented Aug. 30, 1921.

Application filed May 31, 1921. Serial No. 474,037.

To all whom it may concern:

Be it known that I, JOHN L. KAUFMAN, a citizen of the United States, and resident of 1750 63rd St., Brooklyn, in the county of

5 Kings and State of New York, have invented certain new and useful Improvements in the Processes and Apparatus for Making Natural-Edge Beaver Hats, of which the following is a specification.

10 One of the main objects of this invention is to provide means and processes for making hats, of the type commercially known as, "beavers," in which the exposed edge of the hat brim is finished with a furred or fuzzy

15 napped surface as well as the main flat surfaces and without doubling, binding, welt- ing or cutting.

Another important object is in the provision of means and processes whereby the 20 manufacture of hats of the type mentioned is very considerably expedited over those in common use and the product greatly perfected.

A further purpose is not only to materially shorten the time of making the hat, but also to obviate the necessity for much of the manual labor, these several objects tending to reduce costs and produce superior results.

30 These and other analogous objects, which will later become apparent, are attained by the novel construction, combination and arrangement of parts and employment of processes, hereinafter described and shown 35 in the annexed drawings, forming a material part of this disclosure, and in which:—

Figure 1 is a partial front elevational view of a conventional type of hat press, in an open or in receptive position, showing the 40 application of the invention.

Fig. 2 is a similar view of the same, the parts being in closed or operating position.

Fig. 3 is a central transverse sectional view of the heating chamber or steam chests, 45 showing one of the dies or forming molds in position.

Fig. 4 is a perspective view of the die used during the first operation and its complementary clamp ring.

50 Fig. 5 is a similar view of the die and ring used in the second operation.

Fig. 6 is a fragmentary sectional view of the same showing the parts in operating position.

Fig. 7 is a plan view of an alternative 55 form of ring used with the die shown in Fig. 9.

Fig. 8 is a central transverse sectional view of the same.

Fig. 9 is a perspective view of the brim 60 finishing die and its clamp ring, similar to that shown in Fig. 5 but differing in shape.

Fig. 10 is a transverse sectional view of the same, showing the parts in operating position.

The invention is applicable to the construction of hats made of wool or fur felts and particularly to those made of a fine fabric commercially known as beaver, the same having a raised pile or nap surface resembling the real fur of the animals called 70 beavers.

The edges of the brims of such hats, when ready for blocking have the desired furry appearance in their natural unfinished 75 blanks, due to the process of making, but these edges, in the common procedure of hat making are trimmed to the size and shape required, thus rendering it necessary to resort to welting or binding the edge, in order 80 to produce the requisite finish, the process being costly, both in material and time, and further, the welting is liable to separate thus ruining the hat.

The process employed, as hereinafter described, avoids such methods, retaining the natural furred edge, which may be termed a natural edge, in order to distinguish from those formed by welting, directly from the material, and without subsequent trimming 90 of the blank.

Referring to the drawings, the numeral 15 designates the opposed uprights of the hat press, the same being rigidly connected by tie rods and braces (not shown), and having between them a table or saddle 16 on which rests a steam chest or hollow chamber 17.

In the lower part of this chamber is a perforated steam coil 18 supplied by the pipe 19 from any convenient source and provided 100 with a proper means of control.

A concavo-convex shield 20, supported by legs 21, is disposed over the coil, the same serving to break the jets of steam issuing from the perforations and cause them to be 105 disseminated within the chamber, condensation being conducted away by the pipe 22.

Above the steam coil is an air pipe 23 ar-

ranged in a circle interjacent the wall of the chamber, the same being perforated and supplied by a pipe 24 connected with a source of compressed air, controlled by the valve 25.

5 The top of the chamber 17 is open except for an inner annular flange 17' disposed slightly below its upper edge and acts as a seat for the dies as further on described.

Passing through the uprights 15 are 10 round vertical bars 28, connected at their lower ends by a yoke 29, this yoke being operated by mechanism of any preferred type as for instance a foot lever (not shown).

15 The upper screw threaded ends of the bars carry a beam 30, adjusted by the nuts 31 relative to the table 16 and obviously is moved in unison with the yoke 29.

A crown block 33 is supported on the 20 lower end of a plunger 34 passing through the center of the beam 30 and operated by the lever 35 as is common.

25 A plurality of rods 36 are adjustably held in the beam 30 by nuts 37 and are engaged at their lower ends in a forming ring 38 circumjacent the crown block 33 which, as has been shown, is movable therethrough by action of the lever 35.

As shown in Figs. 3 and 4 the die 40, used 30 in the first operation, is substantially circular in contour and fitted to rest on the flange seat 17' closely within the extending wall of the steam chamber, the die having recesses 41 formed in its edges at the sides and 35 front engaging locating projections fixed in the chamber.

In profile the slope or angle of inclination of the upper face of the die is uniform, although the finished hat may vary at different 40 parts, the sides and ends rarely being alike.

45 A plurality of perforations 42 are formed through the wall of the die in order to permit the distributed steam or cold air to reach the surface of the material undergoing treatment, the heat and moisture of the steam tending to soften and render the material pliable, while the cold air acts to stiffen the same, retaining it in the form imparted by 50 the die.

The clamp ring 45, carried at the lower ends of the rods 36 may be round, or oval as shown in Fig. 4, its lower face being shaped to suit the die and on its upper side 55 are raised lugs 46 into which the rods are screw threaded, its outer edge being beveled as shown.

60 The first operation is to place the hat blank on the die, bring the clamp ring down upon it sufficiently to hold it smoothly and then steam is entered until the blank is sufficiently softened to draw the blank, by operating through the ring, so that the edge of the fabric is flush with the beveled outer 65 edges of the ring around its entire periph-

ery, the surplus material at the center of the blank being disposed in the opening at the center of the die as indicated in Fig. 3.

Thereupon the clamp ring is firmly seated, compressing the material upon the face of 70 the die, steam is entered until the blank is sufficiently softened, the block element 33 plunged down through the ring and opening in the die, producing its shape in the loose material and forming the crown of 75 the hat.

When this has been accomplished the steam is turned off and the cold air admitted to the chamber, cooling the blank and at a proper time the block is raised, then 80 the clamp ring and the hat form removed from the die, the edges of the brim being of proper shape and appearance without trimming.

85 After the required number of blanks have been produced, the die 40 is removed from its bed in the steam chamber 17 and the die 50, shown in Fig. 5, is substituted.

This die has similar locating means, is inclined as at 51 along its margin and contains 90 an annular depression 52 fitted to neatly receive the brim of the hat, its curved portion 53 having perforations 54 for the same purpose as previously indicated, the wall 53 being curved and shaped to produce 95 a roll or like effect as shown.

The ring 55 is substituted for that previously used and is shaped and fitted to conform to the recess in the die; it is also provided with a beveled outer edge 56 which 100 fits the corresponding inclined edge 52 of the recess, thus holding the parts in accurate register while imparting the finished form to the hat.

105 Figs. 7 and 8 show alternative forms of the clamp ring whereby different shapes are produced, the ring 60 being circular and therefore having a curved contact surface 61 to fit the die 40, while the ring 45, as noted, 110 is oval.

The die 65 and ring 70, shown in Figs. 9 and 10 are for finishing purposes similar to those shown in Figs. 5 and 6 except in shape.

115 In this modification the die is beveled upwardly to the central recess 66, which is inclined sharply downward and provided with perforations 67, for admitting heat or cold to the brim, which, as shown is turned upwardly and clamped by the ring 70 which enters therewithin, holding the edge of the hat brim securely after final adjustment, it being understood that the clamp ring is carried and actuated in the manner before described and that the die is fixed upon the 120 chamber 17 in like manner as the other dies.

125 As changes of construction could be made within the scope of the invention, it is intended that all matter contained in the foregoing description or shown in the accom- 130

panying drawings shall be interpreted as illustrative and not in a limiting sense.

Having thus described my invention, what I claim as new and desire to secure by Letters Patent, is:—

1. A device for forming hats comprising, in combination with a press, a chamber carried therein, means for heating and cooling said chamber, a perforate forming die on 10 said chamber shaped to the peripheral and surface contour desired for the finished hat brim, means for locating said die, and means for adjustably clamping the exterior margin of hat brims on said die.
- 15 2. A device for forming hats comprising, in combination with a press, an impervious chamber in said press having an open top, means for heating, cooling, moistening and draining said chamber, a perforate die interchangeably engaged at the top of the 20 chamber, said die being shaped to the peripheral and surface contour of the brim, and a clamp ring complementary to said die operatively engaged with said press.
- 25 3. A device for forming hats, comprising, in combination with a press, a walled chamber having an open top, a perforated steam coil in said chamber, a guard thereover adapted to disseminate steam, a cold air pipe 30 disposed over the chamber, a clamp ring suited to said die adapted to clamp material therebetween over the perforation in the die, the outer edge of said ring being the 35 exact size and shape of the periphery intended for the finished hat brim, and means combined with said press for actuating said ring to give it an initial light, and final firm pressure on said die.
- 40 4. A device for forming hats comprising, in combination with a press, an impervious chamber in said press having an open top, a perforate die interchangeably engaging said chamber, means for diffusing steam in the 45 chamber, a crown block operable through said die by said press, a ring operated by the press adapted to clamp material on the face of said die first lightly and then rigidly, the outer edge of said ring being the exact 50 size and shape intended for the edge of the finished hat brim, and means for cooling the interior of said chamber.
5. A device for forming hats comprising, in combination with a press, an impervious 55 chamber in the press, said chamber having an annular seat surrounding its open top, interchangeable dies fitting said seat, said dies being perforate and containing recesses fitting the brims of the hats and central 60 openings for their crowns, steam diffusing means in said chamber, cooling means for the chamber, plunger carried blocks for the crowns of the hats operated by the press, and interchangeable brim forming rings 65 complementary to said dies operatively en-

gaged in the press adapted to clamp the hat brim under a variable pressure, the outer edge of said ring being the exact size and shape intended for the edge of the finished hat brim.

6. The process of forming a hat which comprises clamping the brim between opposed formed surfaces, applying steam to the lower surface, adjusting the edge of the brim to coincide with the outer edge of the 75 upper surface, plunging the crown, and cooling the hat blank thus formed.

7. The process of forming a hat which comprises disposing the blank upon a form having an opening, applying a clamp over 80 the blank adjacent the edges of its brim, steaming the blank upon the form, drawing the blank toward the center until the edge of the brim coincides with the outer edge of the clamp, plunging the crown of the blank 85 into the crown opening of the form, turning off the steam, and introducing cold compressed air to the blank.

8. The process of making hats which comprises taking a blank having a peripheral 90 contour corresponding to that of the finished brim but having an extending circumferential margin, clamping the brim loosely between rigid formed surfaces, heating the blank to acquire pliability, drawing the 95 blank toward the center until its circumferential edge is in register with the outer edge of said upper surface, increasing the pressure between said surfaces, forming the crown of the hat, and stiffening the blank 100 by the application of cold.

9. The process of finishing a hat which comprises disposing a formed blank within the confines of a depression in a metal die, applying a brim ring shaped complementary to the outer boundary of said depression, admitting steam to the blank, pressing the brim ring firmly into position, inserting a crown block into the blank, cutting off the steam, and introducing a blast of cold 110 air in place thereof.

10. The process of hat finishing which comprises the introduction of a partially formed hat blank into a die having the shape of the finished hat brim formed in its surface, gradually applying a brim ring shaped as a counter part of the die, softening the blank by admitting hot vapor to the blank, forcing the brim ring toward the die to compress the blank therebetween, plunging the hat crown, permitting the blank to become set, and stiffening the blank by the application of cold air prior to removal from the die.

11. The process of forming a hat which 125 comprises disposing the raw blank upon a metal form, applying a clamp ring over the blank adjacent the edges of its brim, admitting steam to the blank, drawing the blank toward the center until the edge of the brim 130

coincides with the outer edge of the clamp ring, plunging the crown of the blank, turning off the steam, and introducing cold compressed air to the blank, reblocking the partially formed blank into a die having the shape of the finished hat brim formed in its surface, gradually applying a brim ring shaped as a counter part of the outer margin of the formed surface, softening the blank by hot vapor, forcing the brim ring to-

ward the die to compress the blank therebetween, plunging the hat crown, permitting the blank to become set, and stiffening the blank by the application of cold air prior to removal from the die.

15

Signed at New York, in the county of New York and State of New York, this 16 day of May, A. D. 1921.

JOHN L. KAUFMAN.
